OTHER PUBLICATIONS

Design U.S. Appl. No. 29/369,763, filed Sep. 13, 2010, Applicant: Minh Sang Tran, Aquaspa 9 Pedicure Spa Base Design.

Primary Examiner — David Muller

(74) Attorney, Agent, or Firm — Jones Walker LLP

(57) **CLAIM**

The ornamental design for a pedicure spa base, as shown and described.

DESCRIPTION

FIG. 1 is a front, left-side prospective view of the pedicure spa base.

FIG. 2 is a rear, right-side prospective view of the pedicure spa base.

FIG. 3 is a left side elevation view of the pedicure spa base.

FIG. 4 is a left-side elevation view of the pedicure spa base.

FIG. 5 is a top plan view of the pedicure spa base.

FIG. 6 is a rear elevation view of the pedicure spa base.

FIG. 7 is a front elevation view of the pedicure spa base; and, FIG. 8 is a front, left-side view of the pedicure spa base showing a pedicure chair and bowl positioned on the pedicure spa base.

The features shown in broken lines, particularly the pedicure chair and basin, depict environmental subject matter only and form no part of the claimed design.
